HEAT-SAVING AND/OR BLACK-OUT
WINDOW SHIELDIsaac Goldmerstein, New York, N. Y., assignor of
thirty-five per cent to George A. Rubisow,
New York, N. Y.

Application February 22, 1943, Serial No. 476,694

20 Claims. (CL 160—354)

This invention relates to a considerable improvement on a new heat-saving shield for windows which can be used simultaneously as a black-out-shield as well.

This device may be manufactured at very low cost being made of very cheap, non-essential materials. It is easy to handle and apply and prevents the escape of heat from heated rooms and simultaneously prevents the penetration of the cold from out-of-doors into the inside.

In cold weather, due to the fact that the air circulating within a room comes into continuous contact with the windows, it becomes itself chilled and descends to the floor. This creates a continuous current of cold air in the room, which, because of the high thermic conductivity of glass, can make the room very cold and exceedingly uncomfortable.

This invention will be found particularly advantageous in inclement weather especially when high winds prevail, as it will prevent cold air from seeping into the house through the crevices in the window frame.

Thus, an average house or room having an average amount of windows (generally 20 to 25% in relation to outside wall space), loses about 70% of its heat and accordingly 70% of the fuel employed.

The present invention provides means to prevent the warm air in the house from coming into contact with the cold window panes. It consists in covering the window panes with a shield made of cardboard or like material having very low thermic conductivity in accordance with one or more of the embodiments herein described.

The shield made in accordance with this invention plays the same role as a double window, but is more efficient, as the warm inside air never contacts the window pane when the shield is affixed thereon. The shield must be made of a good insulating material.

It is known that about eleven times more heat is lost per square foot of a window than per square foot of an ordinary wall.

The window provided with the shield such as described herein will lose a considerably lesser amount of heat calories than will a window without a shield.

The saving of otherwise lost heat effected by the application of these shields, easily reaches 35 to 45%. Hence, practically the same economy in fuel is effected.

Where storm windows are employed, fuel is saved only when strong winds prevail and provided that the storm windows are well constructed

and fit perfectly which is generally only while they are still new. However, since storm windows cannot prevent the inside air from coming into contact with the window panes, they cannot prevent the air from becoming increasingly colder and the chilling of the room goes on as usual.

Venetian blinds and shades also help very little to retain heat in the room, since they, too, are unable to stop the continuous contact of the air in the room against the cold window-panes.

The shield made in accordance with this invention may be affixed to the windows at any time of the day desired. It will be found particularly advantageous by people who go to business, as they can affix the shields to their windows before leaving the house and thus be assured that they will return to warm rooms and at the same time effect a saving of about 50% of heat and fuel otherwise lost.

20 Since this invention is both a heat-saving shield and a blackout shield, it will be referred to in this application simply as a "shield," and no distinction will be made herein between the two uses to which this shield may be put.

25 The above and further objects and novel features will be more fully apparent from the following detailed description when the same is read in connection with the accompanying drawing. It is to be expressly understood, however, that the drawing is for purposes of illustration only, and is not intended as a definition of the limits of the invention.

30 In the drawing wherein like reference characters refer to like parts throughout the several views,

35 Fig. 1 is a cross-section side-view with parts broken out of one embodiment of the shield, with window-frame and walls.

40 Fig. 2 is a schematic front-view of the embodiment shown in Fig. 1.

45 Fig. 3 is another cross-section side view with parts broken out of one embodiment of the shield, with window-frame and walls.

Fig. 4 is another schematic front-view of the embodiment shown on Fig. 1.

Fig. 5 is a schematic cross-sectional side-view of one part of the shield.

Fig. 6 is another schematic front-view of the embodiment shown in Fig. 1.

50 Figs. 7, 8 and 9 are schematic views in perspective with parts broken out of the fixation bars.

55 Fig. 10 is another cross-sectional side-view with parts broken out of one embodiment of the shield, with window-frame and walls.

56

Fig. 11 is a schematical side-view in perspective of another embodiment of the shield.

Figs. 12 and 13 are schematical side-views in cross-section with parts broken out of a part of the shield.

Fig. 14 is a cross sectional view of a modification.

In Figures 1, 2, 3, 4, 6, and 10, 28 is the wall of the room or the framework surrounding the window, 21 is the frame surrounding the window-pane.

In Figures 1 and 2, 23 and 24 are window-shields made in accordance with this invention, of an insulating material such as plain or corrugated cardboard, or any other material such as 15 "Celotex," asbestos, etc. or compressed wood shavings, wood and cement combinations, etc.

Excellent results will be obtained with corrugated cardboard such as used for packing purposes, and even cardboard as thin as $\frac{1}{8}$ " or $\frac{1}{4}$ " 20 or $\frac{1}{2}$ " will prove efficient.

The two shields 23 and 24 are placed as shown on the drawing, Figures 1 and 2, one overlapping the other, for example, 24 overlapping 23. They should be so fitted over the window that they contact the framework 28 surrounding the window in 25, 26 and 27 as closely as possible. To maintain them in that position, a fixation bar 28 is placed in any suitable manner, as for instance, at an angle as shown on Fig. 2, kept in place either by providing the ends of the bar with sharp prongs 29, 30, or as illustrated on Fig. 8 by 31.

Instead of prongs on the ends of the bar, a hook and eye combination may be used, the hooks or the like 32, Fig. 6, affixed to the window frame or the framework surrounding the window, and eyes provided on the fixation bar, shown, by way of example, as 33 on Fig. 7.

Instead of using the prongs or the above combination, one end of the bar may be provided with 40 locking device 33 and the other end with the prong.

One or both ends of the fixation bar may, if desired, be provided with friction fixation means 34, Figs. 3, 4 and 9, such as rubber or other elastic materials, or springs; flexible materials such as thick felt or corkwood, etc., may also be used for this purpose.

Any means used by upholsterers for hanging curtains, i. e. affixing the curtain rods to the window frame, may be used for maintaining the fixation bar in position. A flange 35 shown on Fig. 6 may be attached if desired, either to the window frame or to the framework 36 surrounding the window.

If desired, the shield may also be placed so that it fits to the framework surrounding the window and not the frame surrounding the window panes, as shown in Fig. 6.

Another embodiment of this invention consists in window shields with folds. Where two shields are used, such as shown on Figures 3 and 4, only one may have a fold, or if desired, both of them may have folds, such as shields 37 and 38 provided with folds 39 and 40. A stopper 41 or a plurality of stoppers, 41 and 42, are affixed to shield 37, for instance, in such a position that it overlaps the other shield while simultaneously contacting the frame 43 of the window by its edge 45, if mounted on the window, or the frame 44 of the framework surrounding the window if mounted thereon. Its other edge 46 contacts the stopper 41 and/or 42.

The two shields, either both or only one having a fold, and working as one self-adjustable unit,

made as described above, represent an important aspect of this invention. The shields may be of the same size or one larger than the other. They can be kept in a tight position on the frame of the window by merely pressing them to the frame with the hands and locked in this compressed state by means of the fixation bar 47, in the manner described herein.

An essential feature of this embodiment provides the possibility of fitting the edge 45 of the shield under pressure towards the frame 43 (or 44) while simultaneously pressing the edge 48 of the shield 37 towards the other edge 49 of the window frame (or 50 of the framework surrounding the window).

Additionally, the bottoms 51 of both shields, due to the weight of the shields, will fit perfectly to the bottom edge of the window frame 52, (or the edge of the framework 53 if mounted on the same, as shown on Figs. 1 and 2, for example).

This particular arrangement enables making two shields of cardboard, at least one of which has a fold, the shields being of such dimensions that there will be plenty of reserve for one to overlap the other when placed on the window in the manner herein described. If they are too big, but still overlap one another, the desired results will be achieved just the same. If they are too small but just overlap one another, they will work perfectly also.

Users of this type of shield consisting of two pieces of cardboard, will be able to adjust them to the window by merely cutting them to the proper size. Even if the shield is cut so that the upper edge of the shield, for instance, 54 of Figs. 2 and 6, will not exactly fit the upper edge 55 of the frame, or if, for example, a gap such as shown by 57 on the drawing, even as wide as $\frac{1}{2}$ " or more, will be left, the shield will operate perfectly, as the cold air from the bottom being heavier than the warm air cannot rise to the top of the window. The same phenomena as keeping liquid gases in open bottles occurs.

After placing the two pieces of cardboard on the window frame, or as shown on Fig. 2 on the framework surrounding the window, the user may mark off with a pencil where the stopper 41 or a plurality thereof should be applied in order to provide the pressure of the edges 43, 48 as before described, towards the frame.

In other words, the total width of the both pieces of cardboard, for instance, 37 and 38, when flattened out, should be slightly larger than the width between the edges of the frame (for instance, between 45 and 48, Fig. 4), so that when the two shields are put in position they will exert pressure towards the edges through the intermediary of the stopper.

By this very simple means—two pieces of cardboard, at least one of which has a fold; a stopper (or more than one); and a fastening bar—a perfect window shield which can act to keep out the cold air and simultaneously serve as a blackout shield when desired, is achieved.

The shields may also, if desired, consist of two separate parts that fit into each other in a vertical position, as shown on Fig. 6, for instance, shields 60 and 61 in combination with shields 62 and 63. They may be maintained by one or two fixation bars, as desired. Only one is shown on the drawing.

It will generally be found desirable to provide some free air space between the shields and the window. For this purpose, an insert 64 may

be provided between the window and the shield 23 of Figs. 1 and 2, or insert 65 and/or 68 between shields 66 and 67.

The inserts may be affixed by glue or like means to the cardboard.

Stopper or stoppers 41 may be very small in size or they may be substantially long. The stoppers may even be in the form of a strip as shown on Fig. 4 by 42. They may be affixed to the shield either by prongs, nails, fastening pins, or may be glued thereon.

Figure 6 shows by way of example shields 61 and 63 each having one fold 69, while shields 60 and 62 have no folds.

To provide light in the case that the cardboard is impervious to light, or the material of which the shield is made is opaque, cut-outs 70 or 71, shown on Fig. 11, or 72 shown on Fig. 2, may be made in the shields. The cut-out shown on Fig. 12 wherein the cardboard 72 has a cut-out 73, may, if desired, be covered on one or both sides with glass, Cellophane, or other transparent material 74 or 75. Insert 76 may be used to prevent covers 74-75 from touching.

Figure 13 shows a shield 77 made of corrugated cardboard provided with a cut-out for purposes of light. This cut-out may be made of transparent corrugated Cellophane or cellulose or other suitable plastics.

One of the aspects of this invention offers a new type of corrugated Cellophane or corrugated cellulose material for any use, and in particular, for use in connection with this invention for the manufacture of the shield itself, or for the window (cut-out) in the shield to provide light.

Obviously, instead of fitting the window 79 made of corrugated Cellophane or cellulose into the cut-out made in the shield, it may be simply pasted over the cut-out 72 directly on the shield.

If desired, that edge of the shield which contacts the window-frame, may additionally be provided with a thin flexible edge 80 as shown on Figure 5, made of paper, cloth, Cellophane, cellulose, rubber-band, etc., to increase the tightness between the edge of the shield and the frame.

This is of particular importance where the shield without a fold is used, such as shown on Figs. 1 and 2 for example, which shields may, if desired, be provided with a stopper 181 to augment tightness between the shield edges and the frame. Stopper 181 may also be used if shields 23 and 24 of Figures 1 and 2 are not provided with edges 80 of Figure 5.

Stoppers 41, 42, 181, may be rectangular-shaped and made of any suitable material. In certain cases, they may be trapezoidal, as shown, for example, on Figure 1, where edge 182 of stopper 181 is not perpendicular to the shield.

Where a shield composed of two flat shield parts 23 and 24, Figures 1 and 2, without folds, is used, a stopper of this shape will serve to tighten the edges of the shields towards the frames of the windows or the framework surrounding the window.

If desired, stopper 82, Figure 5, may be additionally provided on its lower part with a cut-out 83 to better engage the edge 84 of shield 85.

The shields may also be provided with more than one fold, as shown by way of example on Figure 10, where the shield-part 66 is provided with only one fold 81 and the shield-part 77 is provided with two folds 82 and 83. Any combination of shields in relation to the number of folds may be used. For instance, a shield-part 75

without a fold and another shield-part having one or more folds may be used together as one unit. Or, a shield-part having one fold and another having one or more folds may be used together as a single unit. The two shield-parts without any folds may also be used as one single unit.

Another aspect of a shield is shown on Figure 14 wherein the glass panes 22 of window-frame 86 are covered with shield-parts 89 and 90. The overlapped shield-part 89 may be quite flat, i. e. having no folds, or it may, if desired, have one or more folds such as shown on Figure 3 or 11. If no folds are provided on part 89 as shown on Figure 14, then it may be advantageous to provide at least one of inserts 87 and 88 to control the air space between pane 22 and the shield.

The overlapping shield-part 90 may have a plurality of zig-zag folds 91, 92, 93, 94, 95, etc. to form a kind of accordion-like device; the last fold 95 may be so placed that the strip of the shield-part from the fold 95 to the edge 96 of the frame, or of the shield-part 90, will be sufficiently wide. Thus, when fastening means 97 is attached, the accordion-like folds, being compressed, extend the width of the shield-part so that it fits the frame; a perfect contact between the edge of the shield-part 90 and the frame 96 is thus provided.

Instead of stopper 181, Figure 2 and Figure 3, or 41-42, Figure 4, tension means such as metal springs or spring made of plastic or elastic means made of rubber, may be used; for instance, as shown on Figure 2, fixation means 98 may be affixed on the frame and fixation means 99 on the shield-part. The tension means 100 may be inserted between 98 and 99 and the shield pulled towards the frame.

If desired, fixation means 101 and 102 may also be affixed on shield-parts 23 and 24, and tension means 103 inserted in between 101 and 102; or the shield-part 38 of Figure 4 may be provided with a cut-out 104, and tension means 107 inserted in between fixation means 105 mounted on shield part 37 and fixation means 106 mounted on a shield-part 38.

Having now ascertained and particularly described the nature of this invention and the manner in which it is to be performed, I declare that what I claim is:

1. In combination with a window having a frame, a heat-saving shield comprising two overlapping shield-parts, the overlapping one and the overlapped one, at least one of said shield-parts being provided with at least one fold preferably parallel to the longitudinal axis of said shield, at least one stopper being provided on one of said shield-parts to contact the edge of the other of said shield-parts, at least one fastening bar with fastening means provided to attach the said shield-parts to said frame.

2. In combination with a window having a frame, a heat-saving shield comprising two overlapping shield-parts, the overlapping one and the overlapped one, at least one of said shield-parts being provided with at least one fold preferably parallel to the longitudinal axis of said shield, at least one stopper being provided on one of said shield-parts to contact the edge of the other of said shield-parts, at least one fastening bar with fastening means provided to attach the said shield-parts to said frame, the width of said shield-parts in the overlapping position being larger than the width of the said frame.

3. In combination with a window having a

frame, a heat-saving shield comprising two overlapping shield-parts, the overlapping one and the overlapped one, each of said shield-parts being provided with a fold, said fold being substantially parallel to the longitudinal axis of said shield, at least one stopper being provided on one of said shield-parts to engage the edge of the other shield-part, a fastening bar and fixation means therefor being provided to attach the said shield-parts to said window.

4. A heat-saving and/or blackout window shield comprising two shield-parts, the overlapping part and overlapped part, at least one of said parts having at least one fold preferably parallel to the longitudinal axis of said shield, a stopper rigidly affixed to one of said shield-parts, a fastening bar and fixation means therefor to attach the said shield to said window.

5. A heat-saving and/or blackout window shield comprising two shield-parts, an overlapping part and an overlapped part, at least one of said parts having at least one fold preferably parallel to the longitudinal axis of said shield, a stopper rigidly affixed to one of said shield-parts, a fastening bar and fixation means therefor to attach the said shield to said window, said shield-parts being made of cardboard.

6. A heat-saving and/or blackout window shield comprising two shield-parts, the overlapping one and the overlapped one, at least one of said parts having at least one fold preferably parallel to the longitudinal axis of said shield, a stopper rigidly affixed to one of said shield-parts, a fastening bar and fixation means therefor to attach the said shield to said window, said shield-parts being made of corrugated cardboard.

7. A heat-saving and/or blackout window shield comprising two shield-parts, the overlapping one and the overlapped one, at least one of said parts having at least one fold preferably parallel to the longitudinal axis of said shield, a stopper rigidly affixed to one of said shield-parts, a fastening bar and fixation means to attach said shield to said window, said shield-parts being made of corrugated cardboard, said stopper being made of wood.

8. In combination with a window having a frame, a heat-saving shield comprising two overlapping shield-parts, the overlapping one and the overlapped one, at least one of said shield-parts being provided with at least one fold preferably parallel to the longitudinal axis of said shield, at least one stopper being provided on one of said shield-parts to contact the edge of the other of said shield-parts, at least one fastening bar with fastening means provided to attach said shield-parts to said frame, one of said shield-parts being provided with at least one cut-out preferably covered with transparent material.

9. A heat-saving and/or blackout window shield comprising two shield-parts, an overlapping part and an overlapped part, at least one of said parts having at least one fold preferably parallel to the longitudinal axis of said shield, a stopper rigidly affixed to one of said shield-parts, a fastening bar and fixation means therefor to attach said shield to said window, said shield-parts being made of corrugated Cellophane.

10. A heat-saving and/or blackout window shield comprising two shield-parts, an overlapping part and an overlapped part, at least one of said parts having at least one fold preferably parallel to the longitudinal axis of said shield, a stopper rigidly affixed to one of said shield-parts, a fastening bar and fixation means therefor to attach said shield to said window, the edges of said shield-parts contacting the said window being provided with flexible flanges.

11. A heat-saving and/or blackout window shield comprising two shield-parts, an overlapping part and an overlapped part, said overlapped part being flat and said overlapping part having at least one fold preferably parallel to the longitudinal axis of said shield, a stopper rigidly affixed to one of said shield parts, a fastening bar and fixation means therefor being provided to attach said shield to said window.

12. A window-shield as set forth in claim 4, wherein the said fastening bar has prongs on both ends.

13. A window-shield as set forth in claim 4, wherein said fastening bar is provided on both ends with rubber tips.

14. A window-shield as set forth in claim 4 wherein the said fastening bar is provided with a hook and the said fixation means comprises a ring in which said hook is inserted.

15. A window-shield as set forth in claim 4 wherein an insert is provided between said shield and said window to provide an air space.

16. A shield as set forth in claim 4 wherein said stopper is attached to said shield-parts by means of prongs.

17. A shield as set forth in claim 4 wherein the said stopper is provided with an edge forming an angle of less than 90° with said shield-parts.

18. A heat-saving and/or blackout window shield comprising two shield-parts, one overlapping the other, at least one stopper rigidly affixed to one of said shield-parts to contact the edge of the other of said shield-parts, a fastening bar and fixation means therefor to attach the said shield to said window.

19. A heat-saving and/or blackout window shield comprising two shield-parts, one overlapping the other, at least one stopper rigidly affixed to one of said shield-parts to contact the edge of the other of said shield-parts, a fastening bar and fixation means therefor to attach the said shield to said window, at least one of the said shield-parts having a plurality of accordion-like folds preferably on the side contacting the window-frame.

20. A heat-saving and/or blackout window shield comprising two shield-parts, one overlapping the other, at least one stopper rigidly affixed to one of said shield-parts to contact the edge of the other of said shield-parts, a fastening bar and fixation means therefor to attach said shield to said window, said stopper having an edge which forms an angle less than 90° with the shield-part to which it is affixed.
